SLICING MACHINE

William J. Campbell, Indianapolis, Ind., assignor
to American Slicing Machine Company, Chi-
cago, Ill., a corporation of New York

Application January 15, 1934, Serial No. 706,716

3 Claims. (Cl. 146—102)

My invention relates to an improvement in slicing machines and has for one purpose the provision of an improved pusher plate for moving the work along a work supporting carriage toward the gauge plate and cutting plane. Another object is the provision of a pusher plate which may be at selection yieldingly or manually operative. Another object is the provision of an improved means for holding a pusher plate at any desired adjustment. Another object is the provision of means for permitting the pusher plate to clear the knife structure and the knife housing and the associated parts at all positions of a work supporting carriage and pusher plate. Other objects will appear from time to time in the course of the specification and claims.

I illustrate my invention more or less diagrammatically in the accompanying drawings, wherein—

- 20 Figure 1 is a front elevation;
Figure 2 is a partial plan view with parts broken away;
Figure 3 is a section on the line 3—3 of Figure 2;
25 Figure 4 is a section on the line 4—4 of Figure 3; and
Figure 5 is a section on the line 5—5 of Figure 3.

Like parts are indicated by like symbols throughout the specification and drawings.

Referring to the drawings, A indicates any suitable base upon which is mounted a motor A¹ which, through a pulley A² and belt A³, drives the knife pulley A⁴ and thereby rotates the knife A⁵. A⁶ is the knife shaft upon which both pulley and knife are mounted.

B is a guard plate for the forward face of the knife which terminates in an arcuate edge B¹ which penetrates the forward depression of the knife. It will be seen that the axis of the knife is somewhat tilted in order to permit this penetration of the guard plate into the hollow of the knife. B² is a cover overlying the upper edge of the knife and the upper edge of the guard plate B. It is mounted on a frame portion B³ which extends upwardly to the rear of the knife A⁵. B⁴ is a scraper mounted upon the guard plate B. It will be observed that the forward face of the cover B², as shown for example in Figure 4, is practically flush with the face of the guard plate B.

In order to prevent any forward projection of any part, I provide locking springs B⁵ which overlie offsets B⁶ on the inwardly projecting upper edge portions B⁷ of the guard plate B. B⁸ is any suitable locking member for holding the cover

B² down in position and thus holding the parts in locked position. It will be observed that there is a cramping connection or engagement between the member B⁵ and the inside of the cover B² when the parts are in locking position, which firmly holds the springs against the offsets B⁶. It will also be noted, as in Figure 4, that the axis of rotation of the knife and knife shaft are tilted slightly from the horizontal in order to permit the forward face of the guard plate B and the corresponding face of the cover B² to be tilted slightly away from the vertical. Two degrees is a fair angle. The purpose of this is to permit the below described pusher plate to clear the guard plate and the cover plate B² at all positions. 5 10 15

C is a gauge plate, the purpose of which is to gauge the thickness of the slices cut. It does not of itself form part of the present invention and it will be understood that any suitable actuating means may be employed therefor for moving it 20 toward and away from the cutting plane.

DD¹ are tracks extending across the forward face of the machine. Slidably mounted upon them is the carriage D² with a work receiving trough including the main surface D³ and the shorter, more steeply inclined surface or flange D⁴. The two are shown as substantially perpendicular to each other. Associated with the carriage structure and particularly with the portion D⁴ of the work receiver are a pair of spaced flanges D⁵D⁶. They are connected at their upper portions by a rod or track D⁷. Positioned upon the member D⁶, for example by being screw threaded into it, is a lower rod D⁸ which has a terminal head D⁹, shown in Figure 4 as adjacent but short 30 35 40 45 of the member D⁶. It is surrounded by a spring D¹⁰, one end of which abuts against the member D⁹ and the other against an abutment D¹¹ which is slideable on the rod D⁸. Slidable with it is the sleeve D¹² to which it may be secured, which surrounds the rod D⁸ and the spring D¹⁰ and which extends through a corresponding aperture in the member D⁶. It terminates in a handle D¹³ whereby the hollow sleeve D¹² may be drawn outwardly through the member D⁶ against the compression of the spring D¹⁰.

Slidable on the rod D⁷ is a sleeve generally indicated as E which is provided with a conic enlargement E¹ which has associated with it an even larger integral cylindrical portion E² which, in turn, connects with another conic portion or boss E³. The portion E² carries a fork E⁴, as will be clear from Figure 3, which partially surrounds the exterior of the shell or sleeve D¹². This will serve to prevent rotation of the member 50 55 55

E^2 about the upper shaft D^7 . The sleeve E is surrounded by an outer sleeve E^5 with which is integrally formed a portion E^6 which extends toward and has associated with it a handle member E^7 . This sleeve E^5 is rotatable about the sleeve E . In order to hold it against undesired rotation and to cause it to hold any adjustment given to it, I provide a thrust member in the form of a spring E^8 which is held on the sleeve E by the collar E^9 . E^{10} is a cylindrical extension of the sleeve E^5 which surrounds the spring E^8 and overlaps the collar E^9 . The effect of the spring E^8 is to thrust the sleeve E^5 in such fashion as to cause a locking engagement against the cone shaped clutch member E^1 . It will be observed from Figure 2 that the opposed engaging surfaces are similarly conic. Therefore, if a spring of sufficient strength is employed, the sleeve E^5 , when it has been manually rotated into desired position, will keep that position because its own weight and the weight of the attached parts is insufficient to cause a relative rotation of the opposed clutch elements. As a positive locking means, I provide the structure shown in detail in Figure 3 and Figure 5. Set in the portion E^2 is an abutment member E^{11} with an inclined face E^{12} . Slidably mounted in the member E^6 is a locking plunger E^{13} which is normally thrust into locking position as by the spring E^{14} . E^{15} is a manual control handle whereby the plunger E^{13} may be moved against the pressure of the spring E^{14} when it is desired to release it. It will be understood that when the parts are moved into the position in which they are shown in Figure 3, the plunger E^{13} overrides the abutment E^{11} , slipping over its inclined face E^{12} . It then drops into locking position because of the expansion of the spring E^{14} . The parts are, therefore, positively locked in the position in which they are shown in Figure 3. When it is wished to release the parts, the operator simply pulls outwardly on the manual handle E^{15} . Its outward movement is limited as by the limit slot E^{16} with the penetrating screw or abutment E^{17} as shown in Figure 3. When the handle E^{15} is moved into unlocking position, the operator can then readily swing the pusher plate structure about the shaft D^7 . In order to limit the rotation of the sleeve E^5 and thus the pusher plate structure, I provide on the sleeve E^5 an abutment E^{20} , which engages an adjustable abutment E^{21} on or associated with the member E^6 .

It will be seen, as in Figure 4, that the abutment D^{11} is rotatable. It is provided with a locking member D^{20} which may be engaged with a corresponding aperture D^{21} associated, for example, with the member E^2 or the fork E^4 . When the member D^{11} is rotated into locking position, then the spring D^{10} controls the movement of the pusher plate structure. When it is moved into the full line or unlocked position of Figure 4, then there is no actuating connection between the spring D^{10} and the pusher plate structure and free manual movement is possible.

G indicates the pusher plate proper. It is pivoted as at G^1 to the arm E^6 on the handle E^7 . G^2 is an arcuate slot through which passes a limiting abutment or screw G^3 whereby the arc of rotation of the pusher plate G in relation to the arm E^6 is limited. G^4 is a spacing abutment which may be of fiber, whereby the lower edge of the pusher plate G , with its teeth G^5 is spaced upwardly away from the member D^3 . The closest approach that is permitted is shown in Figure 1 and the parts are so proportioned that the

teeth G^5 are at all times out of contact with the member D^3 or the teeth mounted on said member.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

In employing a slicing machine of the type herein shown and slicing, for example, a meat such as ham or pork, it is quite advantageous to clamp the work by moving the bottom edge of the pusher plate G against it so that the teeth G^5 engage the work. Where a shorter end of meat is being employed then the pusher plate may be dropped into the position in which it is shown in Figure 1 and may be thrust against the rear of the work. In either case, the operator may advance the work against the gauge plate and toward the cutting plane by urging the pusher plate forward. After the locking member D^{20} is in the full line position in which it is shown in Figure 4, the spring structure is entirely disconnected and the user simply thrusts forward manually against the pusher plate and toward the cutting plane by urging the pusher plate forward. After the locking member D^{20} and the slot D^{21} . By means of the handle D^{13} , he can pull out the sleeve D^{12} , thereby withdrawing, also, the pusher plate structure. He may pull it out far enough to drop the work in front of it or he may clamp the lower edge of the work against the plate. In either case, when he releases the handle D^{13} , the spring D^{10} is free to thrust the pusher plate against the work. In the various uses which may be made of the pusher plate, it is sometimes desirable to lock it upwardly away from the member D^3 . I provide means for so doing, namely; the opposed engaging abutment E^{11} and plunger E^{13} . Furthermore, the clutch structure shown in Figure 2, including the conic member E^1 and the spring E^8 are effective to hold the parts in any position in which they are left, preventing unintended relative rotation of the members E and E^5 .

In order to clear the upper structure of the machine, when the pusher plate G is in the full line position of Figure 3, the knife shaft A^6 may be tilted slightly from the horizontal, permitting the forward face of the guard plate B and the corresponding face of the cover B^2 to be tilted slightly away from the vertical. Two degrees is a fair angle between the guard plate and carriage structure, as illustrated in Figure 4. However, I may tilt the carriage slightly from the horizontal, leaving the knife and associated parts in vertical position and obtain the same results. Likewise, both the carriage structure and the knife structure may be mounted slightly to tilt.

An important characteristic of my device is that the pusher plate structure has two different locking means, one permitting a measure of rotation of the pusher plate assembly and the other positively locking the pusher plate assembly against rotation. It will be understood, in the use of these terms in description and claims, that the rotatable mounting of the pusher plate

alluded to is the mounting of the pusher plate assembly as a whole, namely; its mounting for rotation in relation to the member D⁷. The pusher plate proper is also rotatably mounted 5 in relation to the member E⁶, its rotation being limited by the arc G². This relationship between the pusher plate and its support E⁶ does not of itself form part of the present invention. The positive locking means, including the member E¹³ is important when it is desired positively 10 to lock the pusher plate assembly against rotation in a position above the work support D³. The spring actuated clutch is important in preventing unintended movement of the pusher 15 plate assembly without positively locking it against desired movement. For example, it will prevent any accidental falling of the pusher plate upon the hand of the user. It will also serve as a release in case the operator thrusts 20 the pusher plate down against the work with too great force. Excess pressure may, for example, be applied by a heavy, powerful butcher and the spring actuated clutch connection serves as an automatic release as the spring of the 25 meat itself will force back the member E⁶ or cause a slight clockwise rotation of this member, referring to the position of the parts in which they are shown in Figure 3. This excess pressure, however, can not force the clamp back far enough to release the meat, and the pins G⁵ will still penetrate the meat at the 30 termination of the slight rotation of the member E⁶ leaving the parts in operative position. There is not enough resistance in the friction 35 clutch to prevent the meat from expanding to its normal bulk but there is enough resistance to prevent this expansion from kicking the plate G up and out of holding contact with the meat. Thus the friction clutch acts as an equalizer or 40 governor regulating the pressure with which the clamp will be held against the meat. In the absence of this releasing mechanism it would be possible to clamp meat so tightly that, with some types of drive, the strain back through the 45 mechanism could cause a binding action between the members E⁵ E⁶ and the guide rod D⁷, of sufficient extent to make it difficult, if not impossible, to feed the meat forward. The friction clutch eliminates danger of breaking the 50 arm E⁶ or any other part of the pusher plate assembly because of any violent throwing or

swinging of the pusher plate in its inoperative position. The friction is sufficient to prevent violent or unduly rapid movement of the parts but is insufficient to prevent an intended movement of the parts to any desired position. 5

I claim:

1. In a slicing machine, a base, a knife mounted on said base and means for actuating it, a carriage and means for guiding it across the face and past the cutting edge of the knife, a pin mounted on 10 said carriage in general perpendicularity to the cutting plane, a guide sleeve mounted on said pin and means for holding it against rotation in relation thereto, a pusher plate support including a sleeve slidably and rotatably mounted upon said 15 first mentioned sleeve and a pusher plate mounted on said support, said pusher plate support sleeve and the first mentioned sleeve being provided with opposed clutch surfaces, and means for urging said surfaces normally into clutching relation- 20 ship.

2. In a slicing machine, a base, a knife mounted on said base and means for actuating it, a carriage and means for guiding it across the face and past the cutting edge of the knife, a pin mounted on 25 said carriage in general perpendicularity to the cutting plane, a guide sleeve mounted on said pin and means for holding it against rotation in relation thereto, a pusher plate support including a sleeve slidably and rotatably mounted upon said 30 first mentioned sleeve and a pusher plate mounted on said support, said pusher plate support sleeve and the first mentioned sleeve being provided with opposed clutch surfaces, and means for urging said surfaces normally into clutching re- 35 lationship, including a spring interposed between the two sleeves.

3. In a slicing machine, a base, a knife mounted on said base and means for actuating it, a carriage and means for guiding it across the face 40 and past the cutting edge of the knife, a guide mounted upon said carriage and generally perpendicular to the cutting plane, a sleeve slidably along said guide, means for holding it against rotation thereabout, a second sleeve rotatable in 45 relation to the first sleeve and slidable in unison therewith along the guide, friction clutch means between the two sleeves, adapted to prevent their unintended relative rotation and a pusher plate mounted upon the last mentioned sleeve. 50

WILLIAM J. CAMPBELL.
